(57) **CLAIM**

The ornamental design for a wrist-worn physical activity measurement apparatus, as shown and described.

DESCRIPTION

FIG. 1 is a top plan view of the wrist-worn physical activity measurement apparatus;

FIG. 2 is a top perspective view of the wrist-worn physical activity measurement apparatus;

FIG. 3 is a first end view of the wrist-worn physical activity measurement apparatus;

FIG. 4 is a second end view of the wrist-worn physical activity measurement apparatus;

FIG. 5 is a first side view of the wrist-worn physical activity measurement apparatus;

FIG. 6 is a second side view of the wrist-worn physical activity measurement apparatus; and,

FIG. 7 is a bottom plan view of the body of the wrist-worn physical activity measurement apparatus.

1 Claim, 7 Drawing Sheets
